Primary Examiner — Thomas Johannes(74) *Attorney, Agent, or Firm* — Garvey, Smith, Nehrbass & North, L.L.C.; Brett A. North(57) **CLAIM**

The ornamental design for a shipping and display container, as shown and described.

DESCRIPTION

FIG. 1 is a perspective exploded view of a shipping and display container showing our new design with the upper and lower sections separated;

FIG. 2 is a side exploded view (from first side) with the upper and lower sections separated;

FIG. 3 is a side exploded view (from third side) with the upper and lower sections separated;

FIG. 4 is a side exploded view (from second side) with the upper and lower sections separated;

FIG. 5 is a side exploded view (from fourth side) with the upper and lower sections separated;

FIG. 6 is a top view showing the upper and lower sections separated;

FIG. 7 is a top view of an alternative embodiment showing the upper and lower sections separated with various non-essential design elements in lower section shown in dashed lines; and, FIG. 8 is a perspective view of the upper and lower sections connected to each other.
